PUG MILL

William C. West, Chattanooga, Tenn., assignor to
The West Construction Company, Chattanooga,
Tenn., a corporation of West Virginia

Application February 14, 1950, Serial No. 144,120

2 Claims. (Cl. 259—104)

1

This invention relates to pug mills and more particularly to those employed for mixing relatively heavy and/or large aggregates with more or less cementitious binding material, the invention having for its object to provide a construction which is better adapted to handle this heavy mixture and which is more efficient in use than those heretofore proposed.

With these and other objects in view the invention resides in the novel details of construction and combinations of parts as will be disclosed more fully hereinafter and particularly covered by the claims.

Referring to the accompanying drawings, forming a part of this specification, and in which like parts are designated by like numerals,

Fig. 1 is a vertical sectional view taken along a longitudinal shaft of a pug mill made in accordance with this invention;

Fig. 2 is a vertical transverse sectional view of the pug mill shown in Fig. 1; and

Fig. 3 is an end elevational view of said pug mill.

This pug mill is generally of a well-known type as found in this art, in that it comprises two horizontal parallel shafts passing through a mixing hopper having rounded bottom portions, vertical side and end walls rising from said bottoms, and an open top through which the hopper may be charged with the aggregates to be mixed, there also though optionally being provided heating jackets or chambers associated with the side walls for insuring fluidity of constituency of certain aggregate material having a bituminous character. The shafts preferably are given opposite rotation as by intermeshed drive gears external of the hopper, through the instrumentality of a main drive gear or pulley mounted on one of the shafts, and a plurality of paddles or stirrers are mounted on each shaft within the hopper. This present invention has to deal with the mounting of said paddles and their relationship one to another.

More specifically and with particular reference to the drawings, the hopper is generally identified by the numeral 2, the shafts are indicated at 3 and 4, the intermeshed drive gears are shown at 5 and 6 one of which may (though not necessarily) constitute the main drive gear for rotating both shafts, and the heating jackets are indicated at 7 and 8, see particularly Fig. 3. The bottom of the hopper comprises a substantially semicircular wall portion 9 concentric with the axis of shaft 3, and a similar wall portion 10 concentric with the axis of shaft 4, with a

2 suitable outlet or discharge opening such as 11 at the lowermost portion of each bottom wall, which discharges are controlled by suitable gates such as indicated at 12 operated by a piston such as 13 actuated from the power cylinder 14. The open charging top of the hopper may be suitably closed by any suitable cover not shown but readily understood. The shafts are mounted in bearings such as 15 external of the hopper. 10 Each shaft within the hopper has a polygonal (square as shown) transverse cross-sectional shape as indicated at 20 (see Fig. 2), and upon this squared portion of the shaft are mounted the plurality of paddles or stirrers extending radially from the shaft. It is an important feature of this invention that these paddles are arranged in a series of sets and are of different radial extent, the long paddles such as 21 of a set alternating with shorter paddles such as 22 15 of an adjacent set, each paddle terminating in a flat wear-resisting plate such as 23 removably or replaceably mounted on the paddle arm, which plate has a working face which is angularly disposed to the radial plane of rotation of the paddle 20 so that, in the rotation of the shaft, the aggregate material will be given two directions of movement, one movement being longitudinally of the shaft and the other movement being circular with respect to the shaft, to the end that the 25 paddle assembly will partake of the nature of a screw conveyor. The angularity or set of the plates 23 is such as to move the aggregate material in a direction from an end of the hopper to the central area thereof, and the two shafts 30 are given rotational direction such that said material will be moved circularly from each bottom area of the hopper upwardly at the central portion of the hopper, see particularly the directional arrows in Fig. 2.

40 The purpose of providing the long paddles 21 is to insure movement of the aggregate material lying closely adjacent to the inner surface of the hopper, and the purpose of providing the short paddles 22 is to insure movement of the material lying closely adjacent the shaft and so prevent a balling or collection of the material next to the shaft. The short paddles therefore are instrumental in moving said material into the circular or radial path of the long paddles. 45 The circular orbit of at least the long paddles of a shaft overlaps the circular orbit of the paddles of the other shaft as clearly indicated in Fig. 2, to insure positive movement of all of the material in the hopper.

50 The innermost end of each paddle terminates

in a half-bearing 24 adapted to fit the squared portion of its shaft and, when two radially opposed similar paddles are applied to the same shaft, the half-bearings of each are secured together as by the bolts 25. The inner surface of each half-bearing is provided with rectangular (polygonal) notches to fit the corresponding edges or corners of the polygonal portion of the shaft so that the assembly of the paddles on the shaft may be the same as or different from that illustrated in Fig. 2. The polygonal shape of a shaft may be as desired, but in any event the inner surface of each half-bearing will be complementary formed with respect to the angles, edges or corners of the polygonal shaft.

Any number of paddles may be mounted longitudinally of a shaft, there being shown the maximum in Fig. 1 by virtue of the fact that the paddle half-bearings are in sidewise abutting relation throughout the length of the shaft within the hopper. If a lesser number of paddles is desired than that shown, then spacing collars will be provided between the paddles. The angular setting of the plate 23 of a paddle may be effected by imparting a twist indicated at 26 to the outer end of the shank of the paddle in the casting thereof, and each plate 23 is secured in place on its paddle shank as by a square-headed bolt indicated at 27, or equivalent means, for ready replacement when unduly worn. The square head of the bolt is countersunk in the plate so as to provide for one of a plurality of selective arrangements (four) of the plate on the paddle; in other words when the outermost edge such as 28 of a plate becomes unduly worn, the bolt may be withdrawn and the plate turned through 90° to cause another of its edges such as 29 to become the outermost edge.

Whereas the foregoing constitutes a description of the specific construction shown in the drawings, it is to be understood that variations of said constructions are possible and contemplated, wherefore the following remarks are presented as a general statement of the basic inventive idea and the purposes and effects accomplished thereby.

Pug mill mixers have been, for many years, the subject of great study and many experiments to (a) improve the quality of asphalt paving or other mixtures, (b) reduce the mixing time per batch, to result in increased production, (c) reduce the power required in operation, and (d) reduce the amount of wear, particularly to expensive manganese steel liners. In pug mill mixers the various mixtures require different periods of time to obtain a homogeneous mass. Asphalt paving specifications generally require a minimum of from 45 seconds to one minute per batch, or until thoroughly mixed. It has long been known that some minerals aggregate and some mixtures cannot be thoroughly mixed in the minimum time period permitted. As the overall capacity of an entire asphalt plant is limited by the mixer capacity, all plant manufacturers have in recent years built larger mixers, but there is a limit to size as well as other objections.

Applicant discovered some time ago that smaller mixers, having shorter mixing paddles, produced a more thorough mixture than larger mixers with long mixing paddles. The conclusion was that in the larger mixer there existed an area or zone around the mixer shafts wherein the mixing blades on the paddle extremities did not thoroughly agitate and mix the aggregates

with the asphalt cement. The present invention is the solution to this situation and wherein there was installed in a larger mixer both long and short paddles, the short paddles being of further benefit by replacing spacing collars heretofore used between each pair of paddles. The results from this solution have gone far beyond expectations and were indeed surprising, in that they provided,

(a) An improved quality of mixture resulting from two "mixing zones"; one (the outer) zone being that created by the rotation of the longer paddles; and the other zone being created by the rotation of the shorter paddles and disposed within the first or outer zone.

(b) A reduction in the time required to thoroughly mix the aggregates and asphalt cement by reason of the same two mixing zones.

(c) A reduction in the power required in operation by reason of the additional short paddles, keeping a larger quantity of aggregates somewhat in suspension by the upward throwing action of the short paddles.

(d) A reduction in destructive effects of abrasion caused by aggregates against the hopper bottom and walls. The same two mixing zones accomplish this by keeping more of the mixture upward and away from the bottom and side walls.

Therefore, the basic and novel principle is seen to reside in the provision of two mixing zones, one within the other, for the ingredients being mixed, whether they be for asphalt paving or other uses, the paving ingredients being selected herein only as an example. The two mixing zones are represented in Fig. 2, the inner zone being approximately limited by the dot-and-dash line 30, and the outer zone being outwardly limited by the hopper walls and the dot-and-dash line 31. These two zones provide a more homogeneous resultant mixture regardless of the specific ingredients, and additionally insure a more positive agitation in the areas adjacent the hopper walls and adjacent the shafts.

The setting of the blades, for movement of the material from the ends toward the center of the hopper, is optional with an alternate setting of the mixing paddles whereby the material may be circulated around the periphery of the hopper. Some states require the movement toward the center, others the "run-around" action. Further, the ingredients for the mix are acted upon as two contiguous portions, one portion circulated by the paddles of shaft 3 rotating in one direction, and the other portion circulated by the paddles of the oppositely rotating shaft 4, both circulating portions being substantially tangent to and merging with each other; and the ingredients in both zones of each portion being in contact with each other during circulation by virtue of there being no dividing wall between the zones nor between said portions.

It is obvious that those skilled in the art may vary the details of construction and arrangements of parts without departing from the spirit of this invention wherefore it is desired not to be limited to the exact foregoing disclosure except as may be required by the claims.

What is claimed is:

1. A pug mill or the like comprising a hopper, a pair of horizontally disposed parallel shafts extending longitudinally of said hopper with drive connections for rotating said shafts in opposite directions, and a plurality of paddles extending 75 radially from each shaft for agitating the ma-

terial within said hopper, said paddles arranged in alternating sets along each shaft, the paddles of one set comprising a pair mounted upon a shaft in diametric radial opposition to each other and of equal length, the paddles of the adjoining set comprising a pair mounted upon the same shaft in diametric radial opposition to each other and of equal length, the pair of paddles of the one set being of a length different from the length of the pair of paddles of the adjoining set, 10 each paddle fitted at its outer end with a flat plate the working face of which is angularly disposed to the radial plane of rotation of the paddle, the paddles of said alternating sets by virtue of their different lengths adapted to create two mixing zones, one zone disposed within the other zone.

2. A pug mill or the like comprising a hopper, a pair of horizontally disposed parallel shafts extending longitudinally of said hopper with drive 20 connections for rotating said shafts in opposite directions, and a plurality of paddles extending radially from each shaft for agitating the material within said hopper, said paddles arranged in alternating sets along each shaft, the paddles of one set comprising a pair mounted upon a shaft in diametric radial opposition to each other and of equal length, the paddles of the adjoining set comprising a pair mounted upon the same

shaft in diametric radial opposition to each other and of equal length, the pair of paddles of the one set being of a length different from the length of the pair of paddles of the adjoining set, each paddle fitted at its outer end with a flat plate the working face of which is angularly disposed to the radial plane of rotation of the paddle, the angular disposition of said plates being such as to tend to move the material from each end of the hopper in a direction toward the center thereof, the paddles of said alternating sets by virtue of their different lengths adapted to create two mixing zones, one zone disposed within the other zone.
